CARPET SWEEPER WITH BRUSH
CLEANING FINGERS

Howard C. Lilly, Sharon, Mass., assignor to
Masury-Young Company, Charlestown, Mass.,
a corporation of Massachusetts

Application October 20, 1947, Serial No. 780,892

4 Claims. (Cl. 15—388)

1

This invention relates to carpet sweepers and has for one of its objects to prevent accumulations of lint, thread, and similar fibrous materials upon the shaft and bristles of the sweeper brush. According to this phase of my invention the design is such that the sweeper is self-cleaning in operation.

Another object is to combine with such a self-cleaning sweeper means for maintaining a suction or vacuum effect behind the brush whereby all debris drawn into the machine, including the fibrous material tending to cling to the brush shaft and bristles, will be carried out of the machine without clogging the machine or otherwise interfering with the efficiency of its action. According to this phase of my invention the design is such as to provide in a single unit a machine which combines the advantages of a self-cleaning carpet sweeper with those of a non-clogging vacuum cleaner.

Other objects and advantages will appear as this description proceeds.

In attaining my objects, I provide a housing open at its under side to the carpet or rug and having at its upper side a hollow handle connecting with a source of vacuum.

Near its front and rear ends the housing is provided with pairs of supporting wheels for frictional contact with the carpet or other surface as the machine is rolled back and forth thereover by means of said handle.

Intermediate of said pairs of wheels the housing is formed with a brush chamber communicating with said handle and within said chamber is mounted a tufted or other sweeper brush which is rotated by said pairs of wheels.

For dislodging from the brush shaft and brush bristles any lint, thread or other fibrous material which tends to cling thereto while the machine is operating, I pivotally mount two sets of spaced cleaning fingers behind the brush and between it and the exhaust passage from the brush chamber to the handle. These fingers automatically swing into engagement with the brush shaft and the brush bristles, respectively, as the machine is moved in a forward direction over the carpet so as to dislodge debris therefrom and automatically lift away from the brush shaft and bristles when the machine is moved in a rearward direction so as to enable the suction to carry the debris thus dislodged from the shaft and bristles out through the exhaust passage of the housing and into any suitable collection receptacle associated with the machine.

2

In the accompanying drawings illustrating a preferred embodiment of my invention:

Figure 1 is a side elevational view, partly in section of a machine in accordance with my invention.

Figure 2 is a top plan view, with the handle portion shown in section, and with a portion of the top of the casing or housing broken away to more clearly illustrate the relationship of the fibre dislodging fingers to the rotatable brush and brush shaft.

Figure 3 is a vertical sectional side elevational view taken on the line 3—3 of Figure 2, and indicated in dotted lines the position automatically assumed by the fibre-dislodging fingers when the machine is moved in a rearward direction, and

Figure 4 is a vertical sectional elevational view, taken approximately on the line 4—4 of Figure 3, the brush driving roll being shown in section.

Referring to the drawings, 10 designates a casing or housing, substantially rectangular as viewed in plan, and having a rounded top. Spaced apart from the ends of the housing 10 are transversely extending partitions 11 which define with the end walls of the housing 10 a pair of chambers 12. Within each chamber 12 at the upper end thereof and integral with the housing 10 is a web 13 (see Fig. 1). In each of the partitions 11 centrally thereof is an opening 14, generally rectangular in form and rounded at the top.

Formed integral with the housing 10 and extending between the partitions 11 and spaced 35 apart from each other and on each side of the openings 14 are longitudinally extending partitions or walls 15 and 16 defining a brush chamber 17. Chamber 17 extends transversely of the housing 10 and terminates in an exhaust opening 18 at the upper central portion of the housing which is provided with a cover 19 secured in position on the housing by screws 20 (see Fig. 3).

Secured by screws 21 to the lower edge of the wall 15 and to the lower edge of the housing 45 10 at its front end is a plate 22. Also secured by screws 23 to the lower edge of the wall 16 and to the lower edge of the housing 10 at its rear end is a plate 24. Plates 22 and 24 close the under side of the housing in the regions 50 designated and function as skid plates.

Within the chambers 12 and secured by screws 25 (see Fig. 4) to the under face of the webs 13 are angle brackets 26, one in each chamber 12. Secured to the downwardly extending portion of 55 each angle member 26, as by rivets 27, and lying

parallel with the bottom of the housing 10, is a plate 28. Adjacent each end of each plate 28 and pivotally attached thereto, is a link 29 (see Fig. 1), and to the lower end of each link 29 is secured one end of a spring 30, the other end of such spring being attached to the lower end of a downwardly extending portion of each angle shaped member 26. Intermediate the ends of each link 29 is pivotally attached one end of a bearing member 31, the other end thereof being formed as a bearing 32.

There are thus two pairs of bearings 32, one pair at the front of the housing 10, and one pair at the rear. Rotatably mounted in the pair of bearings 32 at the front of the housing 10 is a shaft 33, and to permit this shaft to extend between the two bearings 32, the partitions 11 adjacent the wall 15 are cut away, as indicated at 34 (see Fig. 3).

Similarly, in the pair of bearings 32 at the rear of the housing 10 is a shaft 35, and to permit this shaft to extend between the two bearings 32, the partitions 11 adjacent the wall 16 are cut away, as indicated at 36.

Secured to the shaft 33 adjacent the ends thereof and located in the end chambers 12 is a front pair of supporting wheels or rollers 37. Also secured to the shaft 35 adjacent the ends thereof and located in the end chambers 12 is a rear pair of wheels or rollers 38. The wheels or rollers 37 and 38 are all equal in size and diameter. When in position in their respective bearings 32, the shafts 33 and 35 lie parallel to each other and the springs 30 tend to draw the shafts 33 and 35 toward each other.

On the downwardly extending portion of the angle shaped members 26 and below the plate 28 and on the inner face thereof is secured by means of screw 39 a stub shaft 40 (see Fig. 4). There is one stub shaft at either end of the housing 10 and such shafts are in axial alignment with each other.

41 designates a brush shaft or body having formed integral therewith and at each end a cylindrical driving member 42. Each cylindrical member 42 is less in diameter than the diameter of the wheels 37 and 38 and when in position members 42 are engaged and driven by the peripheral faces of the wheels 37 and 38 which are maintained in driving engagement therewith by the springs 32. The outer ends of the cylindrical members 42 each have formed therein axially of the cylindrical members 42 and the brush body 41, a recess 43 in which the stub shafts 40 detachably seat. The brush body adjacent the cylindrical members 42 is reduced slightly in diameter to permit free movement in the openings 14.

Inserted into the brush body 41 about its periphery, and along its length, are tufts 44 of hair, bristles or other suitable material.

When the apparatus is moved to the right, as viewed in Fig. 1, the wheels or rollers 37 and 38 rotate in the direction of the arrows shown thereon, and consequently the brush shaft or body 41 rotates in the direction of the arrows shown thereon, and the tufts 44 engaging with the surface of a carpet or rug sweep the dirt upwardly into the exhaust opening 18.

Secured to the top of the wall 16 by screws 45 and lying parallel to but spaced apart from each other, are forwardly extending bracket members 46. Secured to the bracket members 46 and extending parallel to but above the brush shaft or body 41 is a pivot shaft 47. Pivotally mounted

on shaft 47 and extending forwardly, as shown in Fig. 3, and with their forward end riding on the brush shaft or body 41 is a plurality of spaced cleaning fingers 48. These fingers 48 are so spaced on pivot shaft 47 with relation to the tufts 44 as to ride on the brush body 41 between said tufts, as clearly shown in Fig. 4. Spacers 49 may be employed to maintain proper spacing between the fingers 48.

10 Also pivotally mounted on shaft 47 and extending forwardly, as viewed in Fig. 3, is a plurality of cleaning fingers 50, these being spaced along the shaft 47 so as to be normally in position to be engaged by the tufts 44 as the brush rotates, and being shorter than the set of fingers 48.

The fingers 48 and 50 are shown in normal operative position in full lines in Fig. 3, and to maintain such fingers 48 and 50 at all times in proper position relative to each other, I provide the shaft 51 which extends through the fingers and lies parallel to the shaft 47.

When the apparatus is being pushed in a forward direction, or to the right as viewed in Fig. 3, the fingers 48 and 50 are in the full line position and the free end of the fingers 48 ride on the brush body 41 and the fingers 50 are in position to engage with the ends of the tufts 44. Any thread, lint, or other fibrous material that 30 may tend to cling to the brush body or to the tufts 44 will be accumulated on top of the fingers 48 and 50 so that when the machine is moved in a rearward direction such debris will be tossed into the area of greater suction by the movement of the fingers to their dot and dash position, which movement is accomplished by the rearward motion of the machine causing the brush and brush shaft to rotate in clockwise direction and thereby elevate the fingers.

40 The cover 19 has rotatably mounted thereon a cylindrical sleeve 52 (see Fig. 3) rotatable on a horizontal axis. This sleeve has two openings, an opening 53 at the top and an opening 54 at the bottom. The opening 54 at the bottom registers at all times with an opening 55 in the cover 19. The sleeve 52 has secured thereto a fitting 56 to which is attached the lower end of a tubular handle 57. The handle 57 is connected by tube 58, to a source of vacuum by means of which suction is maintained through the apparatus and through the handle 57 in the direction of the arrow.

The cover 19 has formed therein a milled groove 59 (see Fig. 3) in which the head of a rivet 60 in the cylindrical sleeve 52 is guided. Secured to the cover 19 is a latch spring 61 which when the handle 57 is in vertical position engages with the rivet head 60 and holds the handle 57 in an upright position when the machine is not in operation.

Having thus described my invention, what I claim as new is:

1. In a carpet sweeper, the combination of a housing, a brush rotatably mounted therein and having a cylindrical body and a plurality of tufts extending radially outward therefrom, a common pivot shaft in parallel spaced relation to said brush, two series of fingers pivotally mounted on said shaft and extending into the brush with one series of fingers in engagement adjacent their ends with the body of the brush and the ends of the other series of fingers in engagement with the tufts of the brush, a shaft lying parallel to said common shaft and extending through said two series of fingers for locking the series of fin-

gers together to act as a unit in pivoting on their common shaft, whereby upon rotation of the brush in a direction toward the ends of the fingers fibrous material collected on the brush will be removed therefrom and led outwardly of the brush and upon movement in a direction away from the ends of the fingers said two series of fingers will rotate as a unit to a position outside the path of said rotating brush.

2. A combined vacuum cleaner and sweeper comprising a wheeled housing, a brush extending transversely of the housing and rotatable by the wheels of the housing as the machine is moved over the floor, a suction chamber at the top of the machine above the brush, said chamber having walls converging to an exhaust passage adapted to be connected with a source of vacuum, and a plurality of pivotally-mounted brush-cleaning fingers between the brush and the exhaust passage, the fingers engaging the brush to strip fibrous material therefrom when the brush is rotated against the ends of the fingers, and the fingers swinging outwardly of the brush when the brush is rotated in the opposite direction, at least some of the fingers being longer than the width of the suction chamber so as to span said chamber when moved outwardly of the brush.

3. A carpet sweeper comprising a wheeled housing, a brush extending transversely of the housing and rotatable by the wheels of the housing as the machine is moved over the floor, said brush having a cylindrical body and a plurality of tufts extending outwardly therefrom, a plurality of long and short brush cleaning fingers disposed in spaced substantially aligned relation transversely of the housing, means for supporting said fingers for rocking movement about an axis parallel to and spaced from the brush, the long fingers extending into contact with and resting upon the cylindrical body of the brush between

tufts and the short fingers extending into and combing through the outer ends of the brush tufts, when the brush is rotated toward the fingers, and said fingers being rocked outwardly of the tufts when the brush is rotated in the other direction.

4. A carpet sweeper comprising a housing, a brush rotatably mounted therein having a cylindrical body and a plurality of tufts extending outwardly therefrom, a plurality of long and short brush cleaning fingers disposed in spaced substantially aligned relation transversely of the housing, means for supporting the fingers with the short fingers in fixed relation to the long fingers, means for mounting the support for pivotal movement about an axis parallel to and spaced from the brush to cause the tips of the long fingers to rest substantially tangentially on the brush body between tufts and the short fingers to comb through the outer ends of the tufts, when the brush is rotated toward the fingers, the long and short fingers being rocked as a unit outwardly of the tufts when the brush is rotated away from the fingers.

tufts and the short fingers extending into and combing through the outer ends of the brush tufts, when the brush is rotated toward the fingers, and said fingers being rocked outwardly of the tufts when the brush is rotated in the other direction.

4. A carpet sweeper comprising a housing, a brush rotatably mounted therein having a cylindrical body and a plurality of tufts extending outwardly therefrom, a plurality of long and short brush cleaning fingers disposed in spaced substantially aligned relation transversely of the housing, means for supporting the fingers with the short fingers in fixed relation to the long fingers, means for mounting the support for pivotal movement about an axis parallel to and spaced from the brush to cause the tips of the long fingers to rest substantially tangentially on the brush body between tufts and the short fingers to comb through the outer ends of the tufts, when the brush is rotated toward the fingers, the long and short fingers being rocked as a unit outwardly of the tufts when the brush is rotated away from the fingers.

HOWARD C. LILLY.
